UNITED STATES PATENT OFFICE.

CHARLES K. STOCKLAND, OF MINNEAPOLIS, MINNESOTA.

GRADING-MACHINE.

1,126,117.

Specification of Letters Patent. Patented Jan. 26, 1915.

Application filed May 2, 1914. Serial No. 885,797.

To all whom it may concern:

Be it known that I, CHARLES K. STOCKLAND, a citizen of the United States, residing at Minneapolis, in the county of Hennepin and State of Minnesota, have invented certain new and useful Improvements in Grading-Machines, of which the following is a specification.

My invention relates to grading machines 10 of the type disclosed in my co-pending application, Serial No. 779,766, filed July 18, 1913, and has for its object to provide a grading machine of the standard reversible type having means for lifting the scraper 15 blade and the drawbar or frame connected therewith bodily and rapidly through a considerable range of movement by means of a single lever provided for that purpose. This quick lifting mechanism is in addition 20 to the usual worm-gear lift for lifting independently either side of the scraper blade, and works independently of such worm-gear lift.

My device makes it practicable to do away 25 with the gooseneck drawbar commonly used in connection with wheeled scrapers of the type herein shown and claimed and at the same time obtain the advantages in the matter of clearance and throat room with the 30 use of a straight drawbar or a drawbar all parts of which are in a horizontal plane.

The full objects and advantages of my invention will appear in connection with the detailed description thereof and are particularly pointed out in the claims.

In the drawings, illustrating the application of my invention in one form,—Figure 1 is a plan view of a road scraper embodying my invention. Fig. 2 is a side elevation 40 view showing the scraper blade in lowered position. Fig. 3 is a view similar to Fig. 2 showing the scraper blade in raised position. Figs. 4, 5 and 6 are detail views of the connection of the lifting lever. Figs. 7, 8 and 45 9 are detail sectional views of the bracket supports for the worm gear lifting mechanism.

The road grading machine to which my 50 improvements are applied is what is generally known as a standard reversible grader. This comprises a rectangular frame comprising longitudinal side members 10 and 11 and front and rear crossbars 12, 13. This frame is supported in an upper plane from 55 front wheels 14 by means of standards 15, and from rear wheels 16 by means of up-

right side standards 17 and angularly-disposed tie members 18, said standards and tie members being secured to frame pieces 19, upon which is supported a platform 20 on a much lower level than the plane of the upper rectangular frame. At the front of the frame, in addition to crossbar 12, is another crossbar 21 which has secured centrally thereto a post 22, said post being secured at its lower end to the axle or front truck of the machine. The scraper blade 23 is secured by means of arms 24 to a fifth wheel construction 25, indicated most clearly in Fig. 1, a portion 26 of said construction being rigidly secured to a pair of normally horizontal arms 27, 28. The arms 27, 28 extend forwardly and are rigidly united at 29 with a bifurcated piece 30 which straddles the post 22 and may be provided with an 35 antifriction roller 31 engaging said post on the side away from scraper 23. The frame member is thus connected for traction purposes with the post 22 by means of the members 28, which, as above pointed out, lie in 40 a common plane normally horizontal, the usual gooseneck employed in constructions of this type being omitted.

I will now describe the means by which the scraper blade is suspended and may be 45 lifted bodily, including the draft bars 27, 28, or may be lifted at either end thereof independently of said draft bars. As best shown in Fig. 1, an arm 32 is rigidly attached to draft bars 27, and a similar 50 arm 33 is rigidly attached to draft bar 28. The arms 32 and 33 are connected by means of links 34 with arms 35 and 36 upon the ends of rock shafts 37 and 38. The rock shafts 37 and 38 are journaled at one end in bearings 39 formed 55 on the side of blocks 40, slideable upon arc-shaped standards 41 secured to the respective side frame members 10 and 11. As clearly shown in Fig. 5, the arc-shaped 60 standards 41 are formed of T-iron, and the slides 40 clasp the base of the T member with the flange extending through a slot 42 in the slide 40. The other end of shafts 37 and 38 are journaled in bearings 43 formed 65 on yoke-member castings 44 journaled upon sleeves 45 upon a shaft 46 supported in bearings on the side member 10 or 11, and upon a yoked extension 47 from upright 17, as best shown in Fig. 9. The center of shaft 46 is the center of curvature of the arc-shaped standard 41, so that the slide 40 may 70

oscillate upon said standard about the center of shaft 46. The shafts 37 and 38 have thereon, outside of bearings 42, a worm wheel 48 meshing with a worm 49 upon shaft 46. Each of shafts 46 has thereon a large hand wheel 50, such as is commonly employed in road grading machines. By rotating either of hand wheels 50 as desired, the shafts 37 or 38 will be rocked and arms 35 or 36 oscillated, which will have the effect of lifting one end or the other of the scraper blade 23, as desired. This specific lifting means *per se* is that commonly employed in grading machines of this type. The particular mounting of this lifting means, which in coöperation with other elements permits the scraper blade and draft frame to be quickly lifted bodily independently of the worm-wheel lift, comprises the main features of my invention.

A shaft 51 is journaled transversely between members 10 and 11 near the front end thereof, and has thereon an arm 52 which is pivotally connected at 53 with an arm or link 54 pivoted to the draft frame members 27, 28 at the meeting point thereof. The link 54 is provided with a wing 55 which, when the parts are in the lowered position indicated in Fig. 2, engages the upper portion of arm 52, holding the parts in fixed relation. Another arm 56 on shaft 51 is rigid with arm 52, and is pivotally connected by link 57 with an arm 58 on a shaft 59 pivoted in uprights 60 carried by frame members 10 and 11. Fast on shaft 59, at each end thereof, are links 61 pivotally connected at 62 within a cutaway portion 63 of an arm or link 64, which is pivotally connected to an extension bolt 65 from sliding piece 40 and has a lip portion 66 engaging the back of arm 61 to hold the parts in fixed relative position when the scraper is lowered. Rigid with arm 58 on shaft 59 is a depending arm 67, which is connected by link 68 with the lower end of a lever 69 pivoted intermediate its ends at 70 to a stand 71 carried by cross-bar 13. The lever 69 is locked in position by means of a ratchet and segment 72, of usual construction, carried by stand 70. Springs 73 are connected with arms 61 and the upper ends of stands 41, and are extended by the descent of the scraper blade 23 and draft frame 28. These springs aid in starting the parts upwardly when the lever 69 is operated.

The operation of these devices will be clear from the description above given. The wheels 50 at all times may be used in the usual way to operate the worm-gear lift to lift or lower either end of the scraper blade. If, however, it is desirable to lift the entire scraper quickly for dodging a rock, stump, or for any other reason, the operator may simply pull rearwardly on lever 69. This oscillates the shaft 59, which simultaneously,

through arms 61 thereon connected with blocks 40 and arms 52 connected with the front end of the draft frame, and through arm 56 and link 57 with arm 58, lifts the entire scraper blade and draft frame vertically to the desired height, the connecting yoke member 30 sliding vertically along upright shaft 22. The principal advantage of thus lifting the front part of the draft frame resides in the fact that the blade is lifted quickly throughout all portions thereof, and no gooseneck is required. This would not be the case if the ordinary gooseneck were used and were pivotally connected to the front truck. The blade would not come up uniformly because when in operation the blade is extended obliquely, as clearly shown, and the front part of the blade would be much nearer the point of pivoting than the rear part of the blade. Therefore, for a given lift the rear part of the blade would rise further than the front part. Moreover, the front part of the blade is usually that portion which is most depressed for operation, and, therefore, to clear an obstruction would have to be lifted a greater extent than the rear blade, and in the pivoted gooseneck construction it frequently would be impossible to lift the front portion of the blade sufficiently to clear a given obstruction.

I claim:

1. A road grading machine comprising a wheel-supported frame, a draft frame connected thereto for vertical movement, a scraper blade carried by the draft frame, a plurality of arms connected with and supporting said draft frame and scraper blade, means to move all said arms simultaneously for raising the scraper and draft frame bodily and uniformly throughout its length, and means for moving some of said arms independently of said uniform moving means to position the scraper blade relative to the point of connection of the draft frame with the wheel-supported frame.

2. A road grading machine comprising a wheel-supported frame, a draft frame connected thereto for vertical movement, a scraper blade carried by the draft frame, means supporting said draft frame from the first-named frame at a plurality of points, means for operating all of said supporting means simultaneously to move the entire draft frame and scraper vertically and uniformly throughout its length, and means in said supporting means for automatically locking the draft frame against vertical movement when said draft frame has been dropped into its lowered or operative position.

3. A road grading machine comprising a wheel-supported frame, a draft frame connected thereto for vertical movement, a scraper blade carried by the draft frame, and means for lifting the draft frame and

- scraper blade bodily and uniformly throughout its length, said means comprising a toggle link having means for holding the portions thereof set when said toggle is 5 broken past the central line thereof in one direction for automatically locking the draft frame against vertical movement when said draft frame has been dropped into its lowered or operative position.
- 10 4. A road grading machine comprising a wheel-supported frame, a draft frame connected thereto for vertical movement, a scraper blade carried by the draft frame, a pivoted arm supporting the front of said 15 scraper frame, a pair of oscillating arms supporting the rear side portions of said scraper frame, means for moving all of said arms simultaneously for raising the draft frame and scraper bodily and uniformly throughout its length, and means for oscillating said rear supporting arms independently for lifting either side of the scraper blade independently of said uniform moving means.
- 20 5. A road grading machine comprising a wheel-supported frame, a draft frame connected thereto for bodily movement, a scraper blade carried by the draft frame, a pivoted arm connected with the front end of the draft frame for supporting the same, a 25 pair of slides, means connected with said

slides and operable independently thereof for supporting and adjusting the rear portions of the draft frame, and means for moving said slides and pivoted arm simultaneously for raising the draft frame and 35 scraper bodily and uniformly throughout its length.

6. A road grading machine comprising a wheel-supported frame, a draft frame connected thereto for bodily movement, a 40 scraper blade carried by the draft frame, a pivoted arm connected with the front end of the draft frame for supporting the same, a pair of pivoted brackets, a pair of slides movable in an arc having its center at the 45 center of oscillation of said brackets, shafts journaled in said slides and brackets, arms on said shafts connected with the rear portions of the scraper frame, worm gear mechanism for oscillating said shaft, and means 50 for moving said slides and pivoted arm simultaneously for raising the draft frame and scraper bodily and uniformly throughout its length.

In testimony whereof I affix my signature 55 in presence of two witnesses.

CHARLES K. STOCKLAND.
